US00D646778S

(12) **United States Design Patent**
Brede et al.

(10) **Patent No.:** US D646,778 S
(45) **Date of Patent:** ** Oct. 11, 2011

(54) **MAGNETIC SEPARATION APPARATUS**

(75) Inventors: **Gaute Brede**, Ranheim (NO); **Darren Ellis**, Lommedalen (NO); **Tine Hildisch**, Oslo (NO); **Jeremy (Jez) Mundy**, Fairford (GB); **Lars Nokleby**, Stabekk (NO); **Erlend Ragnhildstveit**, Oslo (NO); **Richard Toften**, Paradis (NO); **Kornelija Zgongc**, Carlsbad, CA (US)

(73) Assignee: **Life Technologies Corporation**, Carlsbad, CA (US)

(**) Term: **14 Years**

(21) Appl. No.: **29/388,118**

(22) Filed: **Mar. 24, 2011**

Related U.S. Application Data

(62) Division of application No. 29/305,042, filed on Mar. 12, 2008, now Pat. No. Des. 637,709.
